Patented Sept. 17, 1912.

UNITED STATES PATENT OFFICE.

JULES H. HIRT, OF EL PASO, TEXAS, ASSIGNEE, BY MESNE ASSIGNMENTS, TO ALLIS-CHALMERS COMPANY, OF MILWAUKEE, WISCONSIN, A CORPORATION OF NEW JERSEY.

GAS-PRODUCER.

1,038,582.

Specification of Letters Patent. Patented Sept. 17, 1912.

Application filed February 14, 1910. Serial No. 543,721.

To all whom it may concern:

Be it known that I, JULES H. HIRT, a citizen of the United States, residing at El Paso, in the county of El Paso and State 5 of Texas, have invented a certain new and useful Improvement in Gas-Producers, of which the following is a specification.

This invention relates to improvements in apparatus for making producer gas.

10 The object of the invention is to provide a producer for making gas from the combustion of a continuous stream of gas-forming combustible material mixed with air and the subsequent combination of gases formed 15 by the decomposition of steam or other endothermic agent and recombination of the resulting gases with the gases evolved by the said combustion.

Another object of the invention is to so 20 construct the producer that the producer gas made therein will be high in percentage of carbon monoxid and methane or marsh gas, and low in percentage of carbon dioxid.

The accompanying drawing illustrates 25 one embodiment of the invention and from a study of the same as described in the specification, a clear conception of the invention may be had.

In the drawing,—Figure 1 is a central 30 vertical section of a gas producer. Fig. 2 is a section of the producer taken on the line II—II of Fig. 1.

Referring to the drawing, the outer shell 4 is preferably circular and has a hollow 35 column 5 disposed centrally therein. This column 5 is built up from the floor of the producer to a point slightly short of the top of the shell where it enters a recess 40 formed in the top of the shell 4. This construction provides for a variation in the 45 relative expansion of the shell 4 and the column 5. The column 5 is pierced near its upper end by a large number of ports 11. These ports 11 form a means of communication 50 between the interior of the shell 4 and the interior of the hollow column 5. The interior of the shell 4 forms a gas generating chamber which is divided into lower chamber 2 and upper chamber 10, by means 55 of an annular ledge 91 projecting inwardly from the shell 4 before leaving annular communicating passage 9 between the ledge 91 and the outside of column 5, and this passage 9 constitutes a centrally disposed 60 passage through which said column extends

A tangentially disposed inlet 1 for gas-forming combustible material mixed with air is formed in the shell 4 near the bottom of chamber 2. Other valve controlled inlets 13, tangentially or otherwise disposed, are 60 passed through the shell 4 near the top of chamber 2. A radial slag port 8 pierces the lower end of shell 4 at the lowest point of the inclined floor of chamber 2. A cleaning port 7 pierces the shell 4 so as to communicate with the lowest part of the interior 3 of hollow column 5. This cleaning port 7 is exteriorly provided with a cover. An off-take pipe 6 connects with the lowest point of the interior 3 of hollow column 5. The 70 shell 4 is centrally provided at its top with a port 12 having an exterior cover and communicating with the extreme upper portion of the interior 3 of hollow column 5.

Operation: Finely divided gas-forming 75 combustible material such as coal-dust or atomized oil is introduced under pressure to inlet 1 into combustion chamber 2, sufficient air to produce complete combustion being supplied until a high temperature is attained in said chamber, ignition having been initially caused. The volume of air admitted is then decreased in such degree that carbon dioxid ceases to be produced, and the resultant gas is carbon monoxid at a 80 temperature of incandescence. The highest temperature is attained in the upper part of the combustion chamber 2, and the gases and material swirl about column 5 within said chamber, and the resultant gas or gases pass 85 through annular passage 9, and, swirling about column 5 in chamber 10, thence pass through ports 11, thence pass downwardly through interior 3 of column 5, and out through off-take pipe 6 to any point desired for storage or use. This use of the producer in passing the gas downwardly through column 5 is where the producer 90 is designed to more permanently fix the gas produced, as the fixing will take place while 95 passing downwardly through the highly heated column 5. If such a use is not desired by the producer and the gas is to be immediately burned in a furnace, for instance, the gas may be passed directly 100 through said furnace through the port 12, which is in that case suitably connected thereto. Steam or other endothermic agent is admitted through inlets 13 to the upper 105 part of chamber 2, increases the swirling 110

action of the combustible material and gases about column 2, if these inlets are tangentially arranged, and at the high temperature decomposes in the presence of the highly heated carbon, forming hydrogen, carbon monoxid, and methane or marsh gas. The formation of the marsh gas is made possible or its decomposition prevented, by the introduction of the steam or other form of moisture, undoubtedly due to the reduction of the temperature by its introduction. The reduction of temperature of course serves to preserve the walls of the furnace from destruction by the high temperatures attained.

The central location of the annular passage 9, as compared with the major portion of the combustion chamber 2, together with the swirling of the combustible material and gases in the combustion chamber 2, prevent the passage of solid materials from the combustion chamber, (but this feature is not broadly claimed herein as it is claimed in application S. N. 465,424, filed Nov. 30, 1908); and any excess of such solid material, and also the fused impurities and ash, may be removed from the exterior and pass through the slag port 8. Any solid material that may possibly blow through ports 11 and pass downwardly through the interior 3 of column 5, will be deposited at the lowest point of said interior 3, and may be removed from the exterior by passing through cleaning port 7.

It should be understood that it is not desired to be limited to the exact details of construction shown and described, for obvious modifications will occur to a person skilled in the art.

It is claimed and desired to secure by Letters Patent,—

1. The combination in a gas producer, of a shell having an inner recess in the top thereof, a hollow column within said shell extending from bottom to top thereof and into said recess permitting of a sliding movement within said recess said column being pierced by ports near one end, the whole forming an annular vertically disposed gas generating chamber, an inlet to said chamber and an offtake pipe connecting therewith through said column and ports.

2. The combination in a gas producer, of a shell, a hollow column within said shell forming a gas generating chamber, said column joining with the shell at top and bottom but constructed to allow for any expansion and contraction relatively thereto due to heating and cooling, ports through said column, an inlet to said chamber and an off-take pipe leading from said column.

In testimony whereof, I affix my signature in the presence of two witnesses.

JULES H. HIRT.
